[57] ABSTRACT

Disclosed herein is a device for automatically varying the operating speed of a cigarette packaging machine in response to the presence or absence of defective groups of cigarettes to be packaged. The device includes a sensing member for sensing the number of cigarettes in a group, and for sensing the amount of tobacco in each cigarette. Control means are provided to maintain the operating speed of the machine at a high rate until a defective group of cigarettes is sensed by the sensing member, whereupon the operating speed is decreased to prevent malfunctions which may otherwise result from operational changes due to the detection of such defective groups. The control means operates to again speed up the machine after a predetermined duration of sensing by the sensing member during which no defective groups of cigarettes are detected.

FIG-1

FIG-3FIG-2FIG-4

DEVICE FOR AUTOMATICALLY VARYING THE OPERATING SPEED IN PACKAGING MACHINES FOR CIGARETTES

BACKGROUND OF THE INVENTION

This invention relates generally to cigarette packaging machines and more particularly to a device for automatically vary the operating speed in high speed cigarette packaging machines which have an output in the order of about 400 packets or packages per minute, such output being substantially higher than that of machines conventionally used in this art.

DESCRIPTION OF THE PRIOR ART

In such high speed machines, as for example the machine disclosed in the U.S. Pat. application No. 721,525 to the same applicant, the cigarettes are first assembled in overlying multi-layered groups, each group having a number of cigarettes corresponding to the desired number to be wrapped in a single packet. The cigarette groups are then checked to ensure the presence of the proper number of cigarettes and to ensure that each cigarette has a predetermined minimum amount of tobacco therein. Finally, the cigarette groups are wrapped by a multi-sheet wrapping, that is, by a first or inner tin foil wrapping, a second or outer paper material wrapping forming the label, and a seal, small stamp or label. When defective cigarettes are detected and excluded during the checking step, certain delays are caused which interfere with the subsequent steps of said wrapping process, thereby causing operative lacks of balance in the machine such as those due to the phase-difference of the wrapping sheets relative to the movement of the cigarette group to be wrapped. Such differences may be a result of the pre-selective abrupt stop in the feeding of one or more of the wrapping materials related to the defective group(s), and the subsequently restored feeding movements at the high operating speed of the machine.

SUMMARY OF THE INVENTION

It is an object of the present invention to obviate the above-mentioned disadvantages by providing a device capable of operating a packaging machine of the above type at two different speeds in accordance with the results of the check carried out on the cigarette groups to be wrapped. The higher rate of speed corresponds to the running speed, also referred to as second speed, which can be reached when no defective cigarette groups are found over a determined time interval wherein the machine operates at a first speed which is lower than said running speed, at the beginning and renewal of the output cycle and when finding defective cigarette groups to be excluded from the machine.

These and still other objects are all attained by the device according to the present invention for automatically varying the operating speed of the high speed cigarette packaging machine which comprises an electric drive motor operable at different speeds, means for forming cigarette groups in a side-by-side arrangement of overlying multi-layers, sensing means for checking said cigarette groups in connection with the number of cigarettes in each group and the filling grade for each cigarette, devices for feeding the wrapping materials to wrap up said cigarette groups in multi-sheet casings,

means controlled by said sensing means for inhibiting said feeding means, upon detection of defective groups of cigarettes, and ejecting means for ejecting from the production line those cigarettes groups which are determined to be defective by the analysis of said sensing means. The device is further characterized by comprising a plurality of first electroswitching means for controlling the electric drive motor to operate at the higher and lower speeds, second electroswitching means for controlling the first electroswitching means, and a timing device for controlling the second electroswitching means, wherein the timing device controls the first electroswitching means to operate the electric drive motor at the lowest of first speed; and, the second electroswitching means, having contacts in series with contacts of a pair of third electroswitching means located in the feed network and in turn respectively connected to the sensing means and manually controlled switches, controls the first electroswitching means to operate the drive motor at the higher speed.

BRIEF DESCRIPTION OF THE DRAWINGS

Further features and advantages of the device according to the invention will become more apparent from the following detailed description of a preferred embodiment thereof, diagrammatically shown by way of example in the appended drawings, in which:

FIG. 1 is a schematic perspective assembly view of the cigarette packaging machine showing the relative positions for some of its components and excluding those components which are located at the end section of the packaging line;

FIG. 2 is a plan view showing the sensing means for checking the presence of cigarettes and the physical quality thereof;

FIG. 3 is a side elevational view according to the direction of arrow A in FIG. 2, showing the same sensing means for checking the presence of cigarettes and the quality thereof; and,

FIG. 4 is an electric diagram for the operation of the present device.

DESCRIPTION OF THE PREFERRED EMBODIMENT

Referring to the above figures, it will be seen that at A in FIG. 1 an assembly is shown for a cigarette packaging machine of the character as described in said U.S. Pat. application No. 721,525 to the same applicant and wherein at 1 the loading hopper is shown as mounted on a machine frame 2 which feeds overlying layers of juxtaposed cigarettes into the chambers 3 of an endless conveyor 4 which moves forward intermittently.

In the successive chambers 3 of said conveyor 4 the cigarettes are maintained in overlying layers by pushers which are successively arranged to slide on the base plate of the loading hopper 1 to form groups having the desired amount of cigarettes as shown for example in the U.S. Pats. Nos. 3,435,940 and 3,520,394 to the same applicant.

Along the path of said conveyor 4 and on either side thereof groups of sensing means 5 and 6, respectively, are arranged, these sensing means being suitable to detect, in these groups of cigarettes, both the lack of one or more cigarettes and an insufficient tobacco filling therein (see FIGS. 2 and 3).

Sensing pins 7, making up these sensing means, are mounted on supports 5a and 6a reciprocated by shafts 8 and 9 and are so arranged as to face the two ends of each cigarette in the group being sensed. Thus, by means of the shafts 8 and 9, the sensing means 5 and 6 are shifted away from the conveyor 4 until a group of cigarettes is disposed therebetween, whereupon the devices 6 and 7 are moved toward each other. The pins 7 are retained in position by readily compressible springs and the pins probe the ends of each cigarette during the forward movement thereof to give a signal upon detection of any absence of one or more cigarettes or an insufficiency of tobacco in any one cigarette. That is, such faults will result in a free excursion of at least one sensing pin which, through electric contacts and a circuit of a known type (not shown), will cause under these circumstances the coupling of a signal to a control mechanism for the feeding devices of the wrapping materials and to a discharge device for ejecting said defective group, as disclosed for example, in said U.S. Pat. No. 3,530,394. In brief, a piston rod 4a movable through the opening indicated at 4b in the conveyor, and operable in response to the sensing means 5 and 6, will suffice as the discharge device; and, the dispensing operation of the feeding devices of wrapping materials is inhibited by any well known device operably coupled to sensing means.

When the cigarette groups reach the end of conveyor 4, said groups are transferred to the actual packing up line 10 which also receives the wrapping materials from the bobbin rollers 11 and 12 and the device 13, as discussed in great detail in applicant's applicants' Pat. No. 3,495,820.

FIG. 4 illustrates an example of an electrical diagram for controlling the above described high speed packaging machine in accordance with the principle of the present invention, and shows at M an electric motor, such as that designated M132S4/6 CV 4/2,7 manufactured by FIMET, having dual sets of input leads for alternate connections to a potential source to operate the motor according to two different speed rates of the packing machine; two relays or telebreakers TL₁ and TL₂ for controlling said electric motor; three telebreakers R₁, R₂, R₃; a timing-switch element T₁, characterized by a suitable capacitor C, for controlling said telebreakers TL₁ and TL₂; and a pair of push buttons P₁ and P₂, wherein P₁ is the starting pushbutton of the machine and P₂ the stop pushbutton.

A switch contact T₂, associated with the sensing pins 7, closes whenever one of the sensing pins 7 detects the absence of a cigarette in a group, or the unacceptable fill-level of a cigarette, while at C₁ there is shown a cyclic cam which at each machine cycle of the reciprocable shafts 8 and 9 closes and re-opens the contact T₃ which is series-connected with the contact T₂. As indicated in FIG. 4, the series connected switches T₂ and T₃ are also coupled to conductors 14 and 15, which are in turn connected to the control mechanisms for the feeding devices and the discharge device (not shown) for operating those devices as described above.

Finally, TF is a transformer which is connected to the supply current line for the electric motor M and in turn provides a potential source for the telebreakers and timer.

Electrically operated switches as for example telebreakers TL₁ and TL₂ for controlling the electric motor M respectively have four movable contacts TL₁-1, TL₁-2, TL₁-3 and TL₁-4 for engaging the associated fixed contacts TL₁-5, TL₁-6 and TL₁-7 and TL₁-8, and three movable contacts TL₂-1, TL₂-2, and TL₂-3 for engaging the associated fixed contacts TL₂-4, TL₂-5 and TL₂-6.

Each of the telebreakers R₁ and R₃ have two pairs of movable contacts R₁-1, R₁-2, and R₃-1, R₃-2, and respectively two pairs of fixed contacts R₁-3, R₁-4 and R₃-3, R₃-4, while the telebreaker R₂ has two pairs of movable contacts R₂-2, of which R₂-1 is intended to operate on two fixed contacts, that is R₂-3 and R₂-4, whereas R₂-2 has only one fixed contact R₂-5.

Timer T₁, which has a deenergizing time constant as determined by the capacitance of capacitor C, is normally energized and has a movable contact T₁-1 and a fixed contact T₁-2 which are disengaged while the device T₁ is energized.

The operation of the packing up machine embodying the speed varying device according to the present invention is as follows:

At the beginning, the starting pushbutton P₁ is depressed, thereby energizing the telebreaker R₁ so that the movable contacts R₁-1 and R₁-2 close on the fixed contacts R₁-3 and R₁-4, respectively. The telebreaker R₁ is kept selfenergized through its self-energizing circuit closed by contact R₁-2 on R₁-4, while upon the closure of contact R₁-1 on R₁-3 the energizing circuit for telebreaker TL₁ is connected through the movable contact R₃-1 closed on the fixed contact R₃-3 of the de-energized telebreaker R₃, and the movable contact R₂-1 closed on the fixed contact R₂-3 of telebreaker R₂ which is also de-energized.

Upon its energization, the telebreaker TL₁ closes the movable contacts TL₁-1, TL₁-2 and TL₁-3 respectively on the fixed contacts TL₁-5, TL₁-6 and TL₁-7; and a supply current is applied to the bipolar motor M through these contacts so that the motor approaches its lowest or first speed.

As telebreaker TL₁ is energized, its contact TL₁-4 is also opened, thereby causing the de-energization of the timing switch T₁ after a delay determined by the characteristics of capacitor C.

The closure of the movable contact T₁-1 on the fixed contact T₁-2 of the timer T₁, following such a delay causes the energization of telebreaker R₂ and the ensuing closure of its movable contacts R₂-1 and R₂-2 respectively, on the fixed contacts R₂-4 and R₂-5. Upon such movement, said contact R₂-1 will cause the de-energization of TL₁ and the energization of TL₂, and thus, with the closure of movable contacts TL₂-1, TL₂-2 and TL₂-3 respectively on the fixed contacts TL₂-4, TL₂-5 and TL₂-6, the motor is switched from the first speed to the second or running speed of the packaging machine.

At the same time, the movable contacts TL₁-1, TL₁-2, TL₂-3 and TL₁-4 of the de-energized telebreaker TL₁ will be reset to the starting conditions, and the closure of contact TL₁-4 on TL₁-8 causes timer T₁ to be energized and its contact T₁-1 to be opened. However, the telebreaker R₂ remains energized through its self-energizing circuit which closes through the movable contact R₂-2, which upon energization of said telebreaker R₂ is disposed in contact with the fixed contact R₂-5.

Under normal operating conditions the motor M runs at the second speed and this state is retained until depressing the machine stop pushbutton P₂ which on opening causes the de-energization of the telebreakers R₁ and TL₂ and hence the stopping of motor M; or, alternatively, this operating state will also cease under emergency conditions, that is when the sensing pins 7 of the sensing members 5 and 6 perceive in the chambers 3 of the conveyor 4 the presence of an incomplete cigarette group or the incorrect filling of one or more cigarettes making up one group. In this case, contact T₂, representative of the sensing members 5 and 6, closes and upon closing of contact T₃ of the cyclic cam C₁ the telebreaker R₃ is energized and thus its contact R₃-1 opens with a resulting interruption of the supply current to the second speed telebreaker TL₂ and a spontaneous slowing down of motor M.

The opening of contact R₃-2 of telebreaker R₃ will interrupt the self-energizing circuit for telebreaker R₂ with a resulting movement of its movable contact R₂-1 from R₂-4 to R₂-3 as a preset condition for first speed operation of motor M.

The first speed operation of the motor M then continues until the simultaneous occurrences of the interruption of the energizing circuit for telebreaker R₃ due to opening of telebreaker T₂ and switch T₃ and the termination of the delay period after power is removed from the time-delay switch T₁ by the contacts TL₁-4 and -8.

The passage from first speed to second speed in accordance with the above conditions will thus occur following the characteristic time interval of timer T₁, as long as no defective groups are detected at the termination of said time interval.

Accordingly, in order that the whole system reach the operating or running speed, it is required that a sequence of non-defective groups of cigarettes be present under the sensing elements for a time interval not less than the characteristic time of the timer.

As found in practice, by this device, the abovementioned disadvantages which occur in packaging machines characterized by a high operating speed are totally overcome, which disadvantages are due to the high accelerations undergone by the feeding elements of the wrapping materials upon reaching the running speed.

What is claimed is:

1. In an improved high speed cigarette packaging machine including means for providing cigarettes in groups in which said cigarettes in each group are disposed in a juxtaposed and overlying multilayered arrangement, sensing means for detecting the completion of each said group of cigarettes and the amount of tobacco within each cigarette, ejecting means for ejecting defective groups of cigarettes from the machine, and means for feeding wrapping paper for use in wrapping up said groups of cigarettes in multi-sheet casings, the improvement comprising means for automatically varying the operating speed of said machine, upon the sensing of a defective group of cigarettes, including electrical motor means for driving the machine at two different speeds; first electroswitching means for coupling between a potential source and said electrical motor means for controlling said motor means to operate at said two different speeds, second elec-

troswitching means connected to said first electroswitching means for controlling the energization thereof, time-delay switch means and third switching means connected to said second electroswitching means for controlling the energization thereof, said first electroswitching means being connected to said time-delay switch means for controlling the energization thereof, and means for actuating said third switching means in response to the sensing of defective groups of cigarettes by said sensing means, wherein said motor means is connected by said first electroswitching means to operate initially at the lowest of said two different speeds, whereupon after a delay period, said time-delay switch means actuates said second electroswitching means to switch said first electroswitching means to operate said motor means at the highest of said two different speeds, and wherein said third switching means actuates said second electroswitching means to switch said first electroswitching means to again operate said motor means at said lowest speed upon the sensing of a defective group of cigarettes by said sensing means.

2. An improved high speed cigarette packaging machine as set forth in claim 1, in which said motor means comprises an electrical motor having two sets of input leads for alternate connection to a potential source to operate the motor at said two different speeds, and in which said first electroswitching means comprises first and second relays each having switching contacts connected respectively to said two sets of motor input leads.

3. In an improved high speed cigarette packaging machine including means for providing cigarettes in groups, said cigarettes in each group being disposed in a juxtaposed and overlying multilayered arrangement, sensing means for detecting the completion of each said group of cigarettes and the amount of tobacco within each cigarette, ejecting means for ejecting defective groups of cigarettes from the machine, and means for feeding wrapping paper for use in wrapping up said groups of cigarettes in multi-sheet casings, the improvement comprising means for automatically varying the operating speed of said machine, upon the sensing of a defective group of cigarettes, including electrical motor means for driving the machine at two different speeds; first electroswitching means for coupling between a potential source and said electrical motor means for controlling said motor means to operate at said two different speeds, second electroswitching means connected to said first electroswitching means for controlling the energization thereof to operate said motor at the lowest of said two different speeds for a predetermined period, and for subsequently switching said first electroswitching means to operate said motor means at the highest of said two different speeds, and sensing switch means responsive to the sensing of incomplete groups of cigarettes by said sensing means and connected to said second electroswitching means to control the energization thereof, wherein said sensing switch means actuates said second electroswitching means to switch said first electroswitching means to again operate said motor means at said lowest speed for said predetermined period upon the sensing of a defective group of cigarettes by said sensing means.
